United States Patent

Des. 236,160
Patented July 29, 1975

236,160

APPLICATOR FOR A MAGNETIC RECORDING CLIP FOR SLIDES OR THE LIKE

Donald L. Fischer, White Bear Lake, Minn., assignor to
Minnesota Mining and Manufacturing Company

Filed Nov. 1, 1973, Ser. No. 411,667

Term of patent 14 years

Int. Cl. D16—05

U.S. Cl. D61—1 S

FIG. 1

FIG. 2

FIG. 6

FIG. 4

FIG. 3

FIG. 5

FIG. 7

FIG. 1 is a perspective view of an applicator for a magnetic recording clip for slides or the like showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

I claim:

The ornamental design for an applicator for a magnetic recording clip for slides or the like, as shown and described.
